Primary Examiner — Marie D. Fast Horse(57) **CLAIM**

The ornamental design for an information processing apparatus as shown and described.

DESCRIPTION

1. Information processing apparatus

1.1 : front perspective

1.2 : rear perspective

1.3 : front

1.4 : back

1.5 : top

1.6 : underside

1.7 : right side

1.8 : left side

All broken lines in the drawings depict portions of the information processing system that form no part of the claimed design.
